UNITED STATES PATENT OFFICE.

LEWIS J. BAZZONI, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

MACHINE FOR APPLYING REINFORCING STRIPS TO ARTICLES OF FOOTWEAR.

Application filed January 12, 1923. Serial No. 612,307.

To all whom it may concern:

Be it known that I, LEWIS J. BAZZONI, a citizen of the United States, residing at Swampscott, in the county of Essex and State of Massachusetts, have invented certain Improvements in Machines for Applying Reinforcing Strips to Articles of Footwear, of which the following description, in connection with the accompanying drawings, is a specification, like reference characters on the drawings indicating like parts in the several figures.

This invention relates to mechanism for making a reinforcing strip and applying it to an article and is herein illustrated as embodied in a machine for making such a strip and applying it to an article of footwear such as an arctic.

In the manufacture of artics it is customary in some factories to apply along the top and front edges of the quarter a reinforcing strip which comprises a piece of tape folded double, usually with a cord enclosed in the crease or apex of the fold. Hitherto the making of the strip and the applying of it to the upper of the arctic have been done by hand; and the general object of the present invention is to provide a machine which will perform both operations.

According to one feature of the invention the tape is folded approximately along its longitudinal middle, a cord is directed into the apex of the fold, and the cord and folded tape are pressed together to form the reinforcing strip. In the illustrative mechanism the tape is drawn progressively through a stationary folder by combined feeding and pressing rolls, the cord being introduced into the fold at a locality in advance of that engaged by the rolls.

According to another feature of the invention, the reinforcing strip, as fast as it is made, is applied to the arctic or other article. In the illustrative machine the leading end of the strip is led up through and out upon the surface of a table where the operator places upon it the margin of the leading end of the arctic upper, the work, which includes the strip and the arctic upper, being fed progressively to work-pressing mechanism including a hammer which presses the strip firmly into place. The tape herein

illustrated is that commonly used in rubber shoe factories and consists of so-called "friction fabric" which is coated or impregnated with unvulcanized rubber. Such fabric is tacky and requires no cement either to hold the fold in shape or to hold the strip to the arctic.

These and other features of the invention including certain details of construction and combinations of parts will be described as embodied in an illustrative machine and pointed out in the appended claims.

Referring now to the accompanying drawings,

Fig. 1 is a side elevation of a machine in which the present invention is embodied, certain parts of the frame having been broken away.

Fig. 2 is a front elevation.

Fig. 3 is a detail in perspective showing more particularly the work feeding and pressing mechanisms in one position which they occupy.

Fig. 4 is a similar detail showing the same parts in another position, a piece of work being included in this view.

Fig. 5 is a perspective of the working parts of the machine.

Fig. 6 is a plan of the mechanism for making the reinforcing strip.

Fig. 7 is a perspective of the folder through which the tape and cord are drawn to get them into proper relative position.

Fig. 8 is a vertical longitudinal section through the folder, and

Fig. 9 is a section through adjacent portions of the rolls for pressing the cord and the folded tape together.

Before proceeding to a detailed description of the parts of the machine, a general description of its mode of operation will be given. The purpose of the illustrative machine is first to make a reinforcing strip by folding a piece of tape along substantially its median longitudinal line, running a cord into the crease or apex of the fold and then pressing the cord and folded tape, and second to apply the reinforcing strip thus formed to the margin of an article of footwear such as an arctic.

The tape 100 is led from a reel 11 (Fig. 2) through a folder the cover of which is

indicated at 13 (Figs. 5, 7 and 8) which, as the tape is drawn through it, bends or folds the tape progressively so that it is U-shaped in cross-section. In the cover 13 of the folder is a hole 15 through which the cord 200 passes, said cord being directed into the bottom of the fold. This cord is unwound from a ball or spool (not shown) which is suspended above the machine, and permits the cord to run off it in the same manner that thread runs off and is supplied to buttonhole sewing and similar machines. The tape and cord are drawn through the folder by means of two feed rolls 17, 19 which act not only to feed the reenforcing strip thus formed but to press the sides of the folded tape together and to press the vertex of the fold about the cord. The manner in which this is done is shown best in Fig. 9 in which it will be seen that the cord is at one side of the plane which separates the wings of the fold in the tape, the locating of the cord in this position being made possible by the presence of a groove 21 in the lower part of the roll 19. The reenforcing strip thus formed is led (Fig. 1) between guide rolls 23, and then up through an inclined slot in the work table or support 25. On the work support, the strip lies at one locality between upper and lower feed members 27, 29 (Fig. 4) and at another locality beneath a presser in the form of a hammer 31. The margin of an arctic or other piece of footwear is now laid on the reenforcing strip and the two are fed in unison by the feed members in the direction indicated by the arrow and are pressed together by the hammer. When the desired length of strip has thus been attached to the margin of the arctic, the free portion of the strip is severed from the attached portion by a knife 33 (Fig. 5) which is caused to move up through a slot in the table 25. The margin of the upper of a second arctic may now be placed upon the end of the strip and the strip-laying and attaching operation repeated. With this brief outline of the mode of operation of the machine, a detailed description of its construction will now be given.

Referring first to Figs. 7 and 8, the folder comprises a base 35 which rests in a guideway formed on a support 37, said support being carried by a post 39. The folder is held in adjusted position in the guideway by a binding screw 38 (Fig. 8). The top of the folder is constituted by the cover 13, referred to above, which is pivoted to the base at 43, said cover having at its forward end a downwardly inclined guide 45 to direct the cord 200 into the bottom or apex of the fold in the tape. The passageway in the base, through which the tape is drawn, is wide enough at its receiving end to permit the tape to lie flat. This passageway grows narrower and changes in shape until at its

delivery end it forms with the downward projection on the delivery end of the cover a U-shaped guideway 47, as shown in Fig. 7.

The tape, bent or folded into this U-shape and with the cord in the bottom of the U, is delivered to the bite of the pressing rolls 17, 19 (Figs. 5 and 6) which are carried respectively by vertical shafts 48, 50 to the lower ends of which are fastened respectively gears 49, 51 which mesh with each other. Carried by the shaft 48 is a ratchet 53 engaged by a pawl 55, said pawl being pivoted at 57 to an arm 59 and held in engagement with the ratchet by a spring 61. The arm has at its right-hand end a sleeve 63 loosely mounted on a vertical post 65, said sleeve, as will presently appear, having integral with it the lower feed member 29. Pivoted to the left-hand end of the arm 59 is one end of a link 69 to the other end of which is pivoted an arm 71, the hub of which is fast to the lower end of a vertical rock-shaft 73. Fast to the upper end of this rockshaft is the hub of a second arm 75 having mounted on its upper side a roll 77 which projects into a cam groove 79 formed in a barrel cam 81 which is fast to the driving shaft 83. With this construction it will be evident that rotation of the shaft 83 rocks the vertical shaft 73 and, through the link 69 and arm 59, causes the pawl 55 to turn the ratchet 53 intermittently. The presser rolls 17, 19 are thereby turned in the same manner to press the reenforcing strip and to advance it. The shaft 50, by which the presser roll 19 is carried, is mounted in an arm 85 the hub of which is pivoted on the post 39, the outer end of the arm projecting beyond the shaft 50 and having pivoted to its outer end at 86 one end of a link 87 which extends into a casing 89. The outer end of this link has a head between which and the cap 91 of the casing is held a coiled spring 93. The casing has a curved tail which is pivoted at 95 to a hand lever 97, said lever being pivoted at 99 to an arm 101 the hub of which is pivoted on the shaft 48. Also mounted on the pivot 99 is a detent 103 which is held in engagement with the ratchet 53 by a spring (not shown). By reason of the relative positions of the pivots 86, 95 and 99, the spring 93 normally urges the presser rolls 17, 19 toward each other. When it is desired to separate these rolls in order, for example, to introduce the leading end of the reenforcing strip between them, the hand lever 97 is swung in a counter-clockwise direction as viewed in Fig. 6.

As has been explained, the reenforcing strip, after it has been pressed between the rolls 17, 19, is led up through and upon the top of the flat work support 25. At this stage the margin of the arctic or other article to which the strip is to be applied is laid on the strip in the manner shown in

Fig. 4, the work, including the strip and the arctic, being fed in the direction indicated by the arrow, by upper and lower feed members 27, 29 beneath the hammer 31. The 5 oscillation of the lower feed member 29 through the arm 59, link 69, vertical rock-shaft 73 and arm 75 has been described. It is, of course, desirable that the upper feed member 27 should oscillate in unison with 10 the lower feed member, it being understood that such oscillation takes place when the members are gripping the work as shown in Fig. 4. In order to cause oscillation in unison of the two feed members, the arm 77 15 (Fig. 5) has a socket in its end remote from the rockshaft 73 to receive one end of a rod 105, the other end of the rod carrying a ball 107 which is received in a socket in the hub of an arm 109, the outer end of the arm 20 being fast to the stem 111 of the upper feed member 27. When, therefore, the arm 75 is rocked, the feed members 27, 29 are oscillated in unison. These feed members, in 25 operation, first grip the work, then are oscillated in a forward direction to feed it, then release the work and finally are oscillated in a rearward direction thus completing the cycle. The mechanism for oscillating them has been described. Relative movement of 30 approach to cause them to grip and to release the work at the proper times is brought about by lowering and raising the upper member 27. Loosely mounted on the stem 111 of this member is a headed sleeve 113, 35 between the head of which and the top of the hub of the arm 109 is a coiled spring 115. Resting upon the top of the head of the loose sleeve 113 are the arms 116 of a bell-crank lever 117 which is pivoted to the 40 frame of the machine at 119, the downwardly extending arm of the bell-crank lever carrying a roll which runs in a track in a barrel cam 121, fast on the driving shaft 83. Fast to the stem 111 of the upper feed member 45 27 and located above the arms 116 of the yoke is a collar 123. Thus, when the shaft 83 is rotated the two feed members are oscillated in the manner which has been described, and the upper feed member is forced 50 down yieldingly through the spring 115 to press the work against the lower feed member 29 and is raised positively by contact of the upper surfaces of the arms 116 of the yoke with the collar 123. The oscillations 55 and relative movements of approach and separation of the feed members are so timed that the work is fed intermittently in the direction indicated by the arrow in Fig. 4. The rod 105 is in two parts connected by a 60 turnbuckle 125 so that its length can be varied when the machine is assembled. The ball 107 at the righthand end of the rod is held in the socket in the hub of the arm 109 by a set-screw 127 which is locked in adjusted position by a nut. This construction

enables the arm to swing up and down with the reciprocations of the stem 111.

The hammer or work-presser 31 (Fig. 1) is carried at the lower end of a stem 131 which passes through alined bearings 133 70 in the frame of the machine, said stem having fast to it a frame 135 carrying two spaced rollers 137 between which is located a cam 138 carried at the outer end of the driving shaft 83, rotation of the cam thereby causing reciprocation of the hammer. Cooperating with the hammer (Fig. 3) is an anvil 139 which is located in an opening in the table and supported upon a coiled spring 141. 75 80

The mechanisms for operating the feed members and the hammer are so timed that the work is seized and fed forward while the hammer is in raised position. The hammer descends to press the reenforcing strip 85 against the work, the feed members release the work and swing back into position to seize it again, the hammer rises and the cycle begins once more.

After the desired extent of reenforcing strip has been applied to the arctic, the strip 90 must be cut off. To this end an opening is provided in the table at one side of the feed members through which the knife 33, referred to above, may be projected when desired; and extending over the opening, as best shown in Fig. 3, is a combined strip guide and cutting block 143. The knife 33 (Fig. 5) is fast to one end of an arm 145, 95 the other end of which is pivoted at 147 to the frame of the machine. Pivoted to the arm intermediate its ends at 149 is one end of a link 151 to the other end of which is pivoted at 152 a block 153, said block being received in a guideway formed in an arm 100 155 which is fast to the end of a rockshaft 157. This shaft is rocked continually through an arm 159 the hub of which is fast to the shaft and the outer end of which is pivoted at 161 to the lower end of a rod 163 the upper end of which carries an eccentric strap 165 surrounding an eccentric on the drive shaft 83. Normally the axes of the rockshaft 157 and the pivot 152 are held in alinement so that no reciprocation is imparted to the knife 33. When it is desired to reciprocate the knife, in order to sever the reenforcing strip at the end of the strip-laying operation, the block 153 is moved in the slot 110 in the arm 155 to move the pivot 152 out of alinement with the rockshaft 157. To this end a pin 167, located near one end of the link 151, is received between the arms of a yoke formed at the upper end of an arm 169, said arm being integral with one end of a sleeve 171 which is loosely mounted on a horizontal rod 173. Integral with the other end of the sleeve is a second arm 175 having pivoted to its outer end the upper end of a treadle rod 177. The treadle rod is nor- 115 120 125 130

mally held up in the position illustrated by a spring (not shown), the axes of the pivot 152 and the shaft 157 being thus held in alinement, and the knife held stationary in 5 inoperative position. When, however, the treadle (not shown) is depressed to pull the treadle rod 177 down, the arm 169 is rocked in a clockwise direction, as viewed in Fig. 5, to cause the knife to be reciprocated.

10 Loose on the driving shaft 83 is a sprocket around which and around a sprocket fast to the shaft of an electric motor 179 runs a chain 181. A friction clutch of usual type controlled by a bell-crank lever 182 and a 15 treadle rod 183 furnishes means for applying power to the shaft 83 when desired.

In order to permit ready access to the driving mechanism, the whole frame of the machine, including the overhanging arm at the 20 outer end of which the upper feed member 27 and hammer 31 are mounted, is pivoted about a rod 185 (Fig. 2) which extends along one side of the lower part of the machine and is carried by a substantially flat 25 base plate 187. At the side of the machine opposite to that on which the rod 185 is located, the base plate 187 has an upstanding lug 189 to which is pivoted a latch member 191 having upon its threaded stem two 30 spaced nuts 193 between which is received an ear 195 which is part of the frame of the machine. After the upper of the nuts 193 has been removed and the lower one loosened and the two treadle rods disconnected, the 35 whole frame may be swung about the rod 185.

In the operation of the machine, assuming that the tape and cord have been made into 40 the reenforcing strip by passing through the folder and between the pressing rolls 17, 19, and that the leading portion of the strip has passed between the guide rolls 23 and up through the slot in the table 25, the leading end of the margin of the arctic is placed 45 upon the leading end of the reenforcing strip, and the treadle rod 183 operated to throw in the clutch. The work including the arctic and the reenforcing strip, is fed intermittently by the members 27, 29 and is hammered or pressed during the pauses in the 50 intermittent feed movements by the hammer 31. At the same time, more cord and tape are being folded and pressed so that the reenforcing strip is supplied as fast as 55 it is needed, it being understood that the strip-making mechanism and the work-feeding and pressing mechanism are so timed that the making of the strip and the applying 60 of it to the piece of footwear take place simultaneously in such manner that one portion of reenforcing strip is prepared while another is being applied to the piece of footwear. At the end of the strip-applying operation, the free end of the strip is brought 65 beneath the cutting block 143 and the treadle

177 depressed to cause the knife 33 to sever the strip.

In the manufacture of arctics, the parts of the buckles, that is the so-called tongues and ladders are attached to the upper before 70 the reenforcing strip is applied, one of the ladders being shown at 400 in Fig. 4. These members add considerable thickness to the work in the localities in which they are present and extend for a considerable distance 75 beyond the margin. In order to provide for this condition, the flat work table 25 has upon it no obstructions which might block the passage of the buckle members, and the feed mechanism and hammer are so constructed and operated that the extra thickness of the work at the localities in which the buckle members are attached interferes in 80 no way with the feeding of the work or the applying of the strip.

85 Although the invention has been set forth as embodied in a particular machine, it should be understood that the invention is not limited in the scope of its application to the particular machine which has been 90 shown and described.

Having thus described my invention, what I claim as new and desire to secure by Letters Patent of the United States is:-

1. A machine of the class described having, in combination, mechanism for folding a piece of cord into a piece of tape and for pressing the tape and cord to form a reenforcing strip, mechanism independent of 95 said strip-forming mechanism for applying the strip to a piece of stock and for feeding the strip and the stock, and means for operating said mechanisms in timed relation.

2. A machine of the class described having, in combination, mechanism, including a folder and a pair of pressing members, for folding a piece of cord into a piece of tape and for pressing the tape and cord to form a 105 reenforcing strip, mechanism independent of said strip-forming mechanism for applying the strip to a piece of stock and for feeding the strip and the stock, and means for operating said mechanisms in timed relation.

110 3. A machine of the class described having, in combination, mechanism for folding a piece of cord into a piece of tape and for pressing the tape and cord to form a reenforcing strip, mechanism independent of said strip-forming mechanism, including feeding 115 and pressing members, for applying the strip to a piece of stock, and means for operating said mechanisms in timed relation.

120 4. A machine of the class described having, in combination, mechanism, including a folder and a pair of pressing members, for folding a piece of cord into a piece of tape and for pressing the tape and cord to form a reenforcing strip, mechanism independent of said strip-forming mechanism, including feeding 125 and pressing members, for applying the strip and the stock, and means for operating said mechanisms in timed relation.

130

- the strip to a piece of stock, and means for operating said mechanisms in timed relation.
5. A machine of the class described having, in combination, mechanism for forming 5 a reenforcing strip and mechanism independent of said strip-forming mechanism for applying the strip to a piece of stock and for feeding the strip and the stock, said last-named mechanism including a member 10 for pressing the strip against the stock.
6. A machine of the class described having, in combination, mechanism for forming a reenforcing strip and mechanism independent of said strip-forming mechanism 15 for applying the strip to a piece of stock, said last-named mechanism including members adapted to engage and feed both the stock and the strip and a member for pressing the strip against the stock.
- 20 7. A machine of the class described having, in combination, mechanism for folding a piece of tape to form a reenforcing strip, mechanism independent of the strip-forming mechanism for applying the strip to a piece of stock, and for feeding the strip and the stock, said last-named mechanism including a hammer, and means for operating the mechanisms in timed relation whereby the strip is formed as fast as it is applied.
- 30 8. A machine of the class described having, in combination, mechanism for folding a piece of tape to form a reenforcing strip, mechanism independent of the strip-forming mechanism for applying the strip to a piece of stock and for feeding the strip and the stock, said last-named mechanism including members adapted to engage both the stock and the strip and a hammer for pressing the strip against the stock, and means 35 for operating the mechanisms in timed relation whereby the strip is formed as fast as it is applied.
- 40 9. A machine of the class described having, in combination, a table for supporting a piece of work comprising a reenforcing strip and a piece of stock, mechanism including a pair of rollers for forming the reenforcing strip from a piece of tape, means for leading the strip to the table, means for 45 feeding and pressing the work, a drive shaft, and means for operating the rollers and the work feeding and pressing mechanism from said drive shaft in timed relation.
- 55 10. A machine of the class described having, in combination, a table for supporting in superposed relation a piece of work comprising a reenforcing strip and the margin of the upper of an arctic to which buckle 60 members are attached in such manner that they increase the thickness of the margin at the localities in which they are attached and project beyond the edge of said margin, feed members adapted to feed the work, a hammer for pressing the work, and means 65 for operating the feed members and ham-
- mer yieldingly to provide for the variation in thickness of the work, there being a free and unobstructed space above the table to permit free passage of the buckle members.
11. A machine of the class described having, in combination, a table adapted to support a piece of work comprising a reenforcing strip and a piece of stock in superposed relation, a feed member for engaging the strip, a second feed member for engaging 75 the stock, means including a connection between said members for moving said members in unison to feed the work, and means for pressing the strip against the stock.
12. A machine of the class described having, in combination, a table adapted to support a piece of work comprising a reenforcing strip and a piece of stock in superposed relation, a feed member for engaging the under side of the work, a second feed member for engaging the upper side of the work, means for causing relative movement of approach and separation of the members to grip and release the work, means including a connection between said members for moving said members in unison to feed the work, and means for pressing the strip against 80 the stock.
13. A machine of the class described having, in combination, mechanism for forming a reenforcing strip, said mechanism including a stationary folder and a pair of rollers for drawing the strip through the folder and for pressing the fold, and mechanism 85 for applying the folded strip to the margin 100 of a piece of stock.
14. A machine of the class described having, in combination, mechanism for forming a reenforcing strip, said mechanism including a stationary folder and a pair of rollers for drawing the strip through the folder and for pressing the fold, and mechanism for applying the folded strip to the margin of a piece of stock, said mechanism including feeding means for engaging the strip 105 and the stock and means for pressing the strip against the stock.
15. A machine of the class described having, in combination, mechanism for forming a reenforcing strip, said mechanism including a stationary folder and a pair of rollers for drawing the strip through the folder and for pressing the fold, and mechanism 115 for applying the folded strip to a piece of stock, said mechanism including feeding means for engaging the strip and the stock and a hammer for pressing the strip against the stock.
16. A machine of the class described having, in combination, means for folding a piece of tape, means for directing a cord into the fold, means for pressing the cord and folded tape to form a reenforcing strip, a table to which the strip is led, and means for feeding the folded strip and a piece of stock 125 130

over the table and for pressing the strip upon the stock.

17. A machine of the class described having, in combination, mechanism for forming a reenforcing strip, said mechanism including a stationary folder and a pair of rollers for drawing the strip through the

folder and for pressing the fold, and mechanism for applying the folded strip to the margin of the upper of a shoe.

In testimony whereof I have signed my name to this specification.

LEWIS J. BAZZONI.
